United States Patent Office.

J. H. ALDRICH, OF NASHUA, NEW HAMPSHIRE.

Letters Patent No. 63,686, dated April 9, 1867.

IMPROVEMENT IN CATTLE CARS.

The Schedule referred to in these Letters Patent and making part of the same.

TO ALL WHOM IT MAY CONCERN:

Be it known that I, J. H. ALDRICH, of Nashua, county of Hillsboro, State of New Hampshire, have invented a new and useful Improvement in Railroad Freight Cars. The following is a correct description thereof, with reference being had to the accompanying drawings, and letters marked thereon, making a part of this specification.

My invention consists in constructing the car in such a manner that live stock may be fed and watered while on transportation, with as much utility and economy as when in the owner's stable at home. I will describe its construction and operation.

Figure 1 is a perspective view.

Figure 2, a sectional view.

Letters *a a*, in fig. 1, are a door, that may be opened or closed at pleasure, through which the stock may be fed or watered from the outside of the car. In fig. 2, letters *B B* are one side of a longitudinal trough, with lids placed midway from top to bottom, in order that water may be carried in the lower part, and at the same time the stock may be fed in the top part of the said trough. By means of said lids the necessary supply of water may be carried in the lower part of the feed trough from day to day while the stock are on transportation. Said trough is subdivided with partitions so that each creature has a separate trough. Letters *C C* are stanchions for holding each creature in its respective place.

I am well aware that there are a great variety of feed-boxes and troughs in use, and a very great amount of live stock that is crowded into freight cars and transported, (that suffer pain, hunger, thirst, and death,) all of which I disclaim.

What I do claim as my invention, and desire to secure by Letters Patent, is—

The combination and arrangement of the water and feed trough, separated by the lid, when constructed and used upon a cattle car in the manner and for the purpose herein described.

J. H. ALDRICH.
